UNITED STATES PATENT OFFICE.

MAX A. TIECK, OF DENVER, COLORADO.

LIFE-SAVING SUIT.

No. 870,804.

Specification of Letters Patent.

Patented Nov. 12, 1907.

Application filed September 29, 1906. Serial No. 336,673.

To all whom it may concern:

Be it known that I, MAX A. TIECK, a citizen of the United States of America, residing at Denver, in the county of Denver and State of Colorado, have invented 5 new and useful Improvements in Life-Saving Suits, of which the following is a specification.

This invention relates to life preservers, being especially directed to an improved life saving suit embodying a plurality of impervious fluid receiving 10 pockets or chambers, and has for its objects to provide a comparatively simple, inexpensive device of this character which may be quickly and conveniently donned, one wherein the compartments or pockets may be readily inflated for use, and one which will 15 possess the requisite buoyancy to render it highly effective in action.

With these and other objects in view, the invention comprises the novel features of construction and combination of parts more fully hereinafter described.

20 In the accompanying drawings: Figure 1 is a perspective view of a device embodying the invention, showing the same applied for use. Fig. 2 is a rear elevation of the device. Fig. 3 is a longitudinal section taken on the line 3-3 of Fig. 2. Figs. 4 and 5 are cross sections taken respectively on the lines 4-4 and 5-5 of Fig. 2.

Referring to the drawings, it will be seen that the device is in the form of a one-piece or union suit 1 having a neck opening 2, arm-holes 3, and leg portions 4, there 30 being applied around the openings 3 and lower ends of the leg portions 4 straps or bands 5 and around the openings 2 a neck-band or strap 6, which, together with the straps 5, is preferably composed of leather and cemented to the rubber or other impervious material of 35 which the suit is composed.

The suit is, in accordance with the invention, provided at its back with a pair of main fluid receiving compartments or pockets 7 extended throughout the entire length of the garment from the neck-band to the 40 lower ends of the leg portions 4 and connected for communication one with the other and preferably at the waist-line by means of a connecting duct or passage 8, while formed beneath the arm-holes 3 and at the sides of the garments are pockets or chambers 9 in

turn connected for communication with the respective 45 adjacent pockets 7 by means of ducts or passages 10, there being formed on one of the pockets 9 a tubular nipple 11 with which an air pump 12 of any appropriate form may be connected to inflate the pockets 7 and 9.

Disposed at the front of the suit, which is provided 50 with a front opening 13 leading downward from the neck 2 and to be closed by buckles or other fastening members 14, is a pair of tubular vessels 15 composed of rubber or other suitable impervious material and adapted to receive water or other liquid to be used by 55 the operator, the bottles being provided at their upper ends with nipples 16 disposed within convenient reach of the operator's mouth and through which the contents of the vessels may be drawn.

In practice, the suit is donned in the ordinary manner, after which the opening 13 is closed by means of the fastening members 14 and the pump manipulated for inflating the pockets 7 and 9 with air, which flows from one compartment to another through the passages 8 and 10, as will be readily understood. The bottles 65 are then filled with water or with a stimulating liquid, as may be desired, and the device is ready for use.

It is to be observed that the pockets which conjointly cover the entire surface area of the back portion of the garment and the portions thereof beneath the 70 arms will afford the requisite degree of buoyancy to render the device effective and that the inflating medium within the compartments may be renewed from time to time, as necessary by means of the pump 12.

Having thus described my invention, what I claim is: 75

A device of the class described comprising a garment having a pair of back pockets extended conjointly over substantially the entire area of the rear side of the garment and a pair of side pockets disposed respectively beneath the arms, said side and back pockets being connected for communication one with another, and a pump permanently connected with one of the pockets for inflating all of said pockets. 80

In testimony whereof, I affix my signature in presence of two witnesses.

MAX A. TIECK.

Witnesses:

JAMES F. DUHAMEL,
